DESIGN FOR A TIRE CASING

Charles P. Bedell, Detroit, Mich., assignor to The Pep Boys—Manny, Moe & Jack, Philadelphia, Pa., a corporation of Pennsylvania

Application May 6, 1941, Serial No. 100,811

Term of patent 14 years

To all whom it may concern:

Be it known that I, Charles P. Bedell, a citizen of the United States, residing at Detroit, in the county of Wayne and State of Michigan, have invented a new, original, and ornamental Design for a Tire Casing, of which the following is a specification, reference being had to the accompanying drawing, forming part thereof.

I claim:

The ornamental design for a tire casing, as shown.

CHARLES P. BEDELL.
